SAMUEL S. SHAW, OF NEWPORT, NEW JERSEY.

Letters Patent No. 77,110, dated April 21, 1868.

IMPROVED OYSTER-WINDER.

The Schedule referred to in these Letters Patent and making part of the same.

TO ALL WHOM IT MAY CONCERN:

Be it known that I, SAMUEL S. SHAW, of Newport, in the county of Cumberland, and State of New Jersey, have invented a new and improved Oyster-Winder; and I do hereby declare that the following is a full, clear, and exact description thereof, which will enable others skilled in the art to make and use the same, reference being had to the accompanying drawings, forming part of this specification.

Figure 1 represents a front elevation, partly in section, of my improved oyster-winder.

Figure 2 is a side elevation, partly in section, of the same.

Figures 3 and 4 are detail side views of the same.

Similar letters of reference indicate corresponding parts.

This invention relates to a new device, to be used on boats, for winding up oyster-dredges, and its object is to prevent the reversing of the crank-shaft, in case the dredge strikes against a rock, or some other obstruction.

Heretofore the rope from which the dredge is suspended was generally wound around a shaft, which was provided with a crank, so that it might be turned by the occupants of the boat. Whenever the dredge was arrested by a rock, or some other obstruction in the water, the crank-shaft was, as the boat was moving ahead with more or less speed, caused to suddenly reverse its motion, so as to unwind the rope, and, as the crank was thereby caused to revolve rapidly, bodily injury was not only frequently sustained, but the motion of the shaft could also not be arrested, unless the boat was stopped.

My improved winder is so arranged that, if the dredge is arrested by an obstruction, the drum around which the rope is wound will be automatically thrown out of gear with the crank-shaft, and the latter will not at all be affected by the ensuing backward movement of the drum.

The invention consists in the application of sliding drums around the winding-shafts, and in the device for throwing the same into gear with each other; also, in the device for holding them out of gear, when disengaged by the detention of the dredge.

A, in the drawing, represents the frame of my improved oyster-winder. The same is of suitable size and shape, and made of suitable material, enough to support the winding-gear, and the weight attached to the same. The frame is intended to be set up in an oyster-boat, and in it are the bearings of one or more horizontal shafts, B B, which are each provided with a crank, a, by means of which they can be turned. On each axle, B, is mounted a drum, C, which can turn loose on the shaft, and can also slide on the same. To one end of each drum, C, is arranged and firmly secured a gear-wheel, b, which may mesh into the teeth of a gear-wheel, c, that is mounted on the shaft B, as shown in fig. 1.

By means of a lever, D, which is pivoted to the frame A, and connected with a treadle, E, or some other equivalent device, the drum C can be thrown into gear with the shaft.

To one end of each drum, C, is also secured a ring, d, which is toothed on the face, as shown. F is a toothed segment pivoted to the frame A, opposite to the ring d, and connected with a slotted lever, e, which can be raised by means of a treadle, f, or some other equivalent device.

On the end of the arm F, on one side of the toothed part of the same, is hung a small friction-roller, g, as shown.

The operation is as follows: The rope to which the dredge is attached is secured to the drum C. When the rope is to be wound around the drum, the segment F is raised by means of the lever e, so that when, then, the drum is pushed towards it and the gear-wheel c, by means of the treadle E, the teeth of the ring d will mesh into those of the segment, while, at the same time, the wheels b and c will gear together.

When the crank a is turned, the drum C will also be turned, and the segment will rest against the end of the drum, being raised by every tooth of the ring d, and then again falling, of its own weight, into the space between two teeth. The arm e being slotted, falls as soon as the segment has been brought into position, and does not have its weight upon the segment. All the parts are then in the position shown in fig. 3 of the drawing.

Should the dredge strike against an article, the strain on the rope will at once draw the drum off the wheel *c*, and will thereby disengage the drum from the shaft, so that the rope may unwind without affecting in the least the motion of the shaft.

While the drum is thus drawn back, the segment falls down, until the pin *h*, which fits through the slot in the rod *e*, reaches the lower end of that slot, as in fig. 4. The roller *g* will then, with its edge, touch the end of the drum *C*, and will be revolved by the same, thus not hindering its motion, but the drum *F* will, in this position, prevent the drum from sliding towards the wheel *c*, and from becoming thereby connected with the shaft *B*.

The object of the arm *F* is, therefore, to form a stop for keeping the shaft and drum out of gear, when the rope is unwinding, so that no accident can occur by the crank revolving.

I claim as new, and desire to secure by Letters Patent—

1. An oyster-winding apparatus, consisting of the shaft *B*, sliding drum *C*, gear-wheels *b*, *c*, and *d*, and pivoted segment *F*, all made and operating substantially as and for the purpose herein shown and described.
2. The drum *C*, when arranged so that it can turn and slide on the shaft *B*, and when combined with the gears *b* *c*, and with the lever *D*, all made and operating substantially as set forth.
3. The block *F*, when pivoted to the frame *A*, and when provided with the friction-roller *g*, as set forth.
4. The slotted bar *e*, for elevating the block *F*, in combination with the same, and with the drum *C*, all made and operating as set forth.

SAMUEL S. SHAW.
